BARRICADE AND SIGN

Louie A. Roberts, Jackson, Miss.

Application May 31, 1939, Serial No. 276,729

4 Claims. (Cl. 14—58)

The present invention relates to new and useful improvements in barricades and signs particularly for highway bridges and has for its primary object to provide, in a manner as herein-after set forth, a device of this character which is permanently installed beneath the floor of a bridge and which will be automatically elevated to operative position should the bridge sag, collapse or some other dangerous condition develop.

Another very important object of the invention is to provide an apparatus of the aforementioned character embodying novel means for releasably securing the barricade in lowered or inoperative position below the surface of the bridge floor.

Other objects of the invention are to provide an automatic barricade which will be comparatively simple in construction, strong, durable, highly efficient and reliable in use, compact and which may be manufactured and installed at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a cross sectional view, showing an embodiment of the invention installed on a bridge.

Figure 2 is a view in horizontal section, taken substantially on the line 2—2 of Fig. 1.

Figure 3 is a view in vertical longitudinal section.

Figure 4 is a detail view in cross section, taken substantially on the line 4—4 of Fig. 3.

Figure 5 is a detail view in horizontal section, taken substantially on the line 5—5 of Fig. 3.

Referring now to the drawings in detail, it will be seen that the embodiment of the invention which has been illustrated comprises a pair of housings 1 which are suspended beneath the floor 2 of a bridge 3 adjacent the ends of said bridge.

The bridge floor 2 has formed transversely therein slots 4 which communicate with the housings 1. At the ends of the slots 4 channel guides 5 depend from the floor 2 in the housings 1.

Mounted in the housings 1 and operable vertically in the slots 4 are plates or panels 6 of any suitable construction. The panels 6 travel in the guides 5. The reference numeral 7 designates cables having one end connected to the side portions of the panels 6. The cables 7 are trained over pulleys 8 which are journaled in the upper

portions of the housings 1 and said cables have connected to their other ends counter-weights 9. Openings 10 in the bottoms of the housings 1 accommodate the cables 7. Signs 11 are provided on the upper portions of the panels 6. Plates 12 are secured on the upper edges of the panels 6 for closing the slots 4 in the bridge floor 2.

Mounted on the inner sides of the housings 1 are brackets 13. Slidably mounted in the brackets 13 are bolts 14 which are projected by coil springs 15, said bolts being engageable in the openings 16 which are provided therefor in the panels 6 for releasably securing said panels in lowered or inoperative position. Extending between the bolts 14 is a cable 17 having interposed therein a coupling 18. Guide pulleys 19 are provided for the cable 17. Pivotedly suspended in the housings 1 are gravity actuated dogs 20 which are engageable beneath the panels 6 for positively securing said panels in raised or operative position.

It is thought that the operation of the apparatus will be readily apparent from a consideration of the foregoing. The panels 6 are normally held in lowered or inoperative position against the action of the weights 9 by the spring projected bolts 14 engaged in the openings 16. However, should the bridge sag dangerously or collapse between the housings 1 the bolts 14 will be retracted against the tension of the coil springs 15 by the cable 17 thereby freeing the panels 6. Panels 6 are then immediately raised to operative position above the bridge floor 2 by the weights 9, said panels sliding upwardly through the slots 4. It will thus be seen that the elements 7, 8 and 9 constitute mechanical means for elevating the panels 6. The dogs 20 then swing by gravity beneath the lower edges of the panels 6 for positively locking said panels in raised position. Thus, a barricade and sign is had at both ends of the bridge for preventing the passage of traffic thereover and giving warning that said bridge is unfit for use. If desired, the barricades may be manually released should it be desired to halt traffic for any reason. Of course, the apparatus may be mounted for operation on highways as well as bridges.

It is believed that the many advantages of an automatic barricade and warning sign constructed in accordance with the present invention will be readily understood and although a preferred embodiment of the apparatus is as illustrated and described, it is to be understood that changes in the details of construction and in the combination and arrangement of parts may be resorted

to which will fall within the scope of the invention as claimed.

What is claimed is:

1. In a bridge comprising a floor having slots therein, an automatic barricade comprising vertically slidable panels mounted beneath the floor and operable in the slots, bolts engaged with the panels for releasably securing said panels in lowered position, a member connecting said bolts and extending beneath the floor for engagement and actuation by said floor for retracting said bolts and releasing the panels should the floor fall, and mechanical means for raising said panels to operative position.
- 5 10 15 20 25 30
2. An automatic bridge barricade comprising housings mounted beneath the floor of a bridge at spaced points, said bridge floor having slots therein communicating with the housings, panels slidably mounted in the housings and operable in the slots, bolts releasably securing the panels in lowered position, a member connecting said bolts and extending beneath the floor for engagement and actuation by said floor for retracting said bolts and releasing the panels should the floor fall, and mechanical means for elevating the panels to operative position above the bridge floor when said panels are released.
3. An automatic bridge barricade comprising housings mounted beneath the floor of a bridge at spaced points, said bridge floor having slots therein communicating with the housings, panels slidably mounted in the housings and operable in the slots, bolts releasably securing the panels

in lowered position, a member connecting said bolts and extending beneath the floor for engagement and actuation by said floor for retracting said bolts for releasing the panels should the floor fall, and means for elevating the panels to operative position above the bridge floor when said panels are released, said means including pulleys journaled in the housings, cables trained over said pulleys and having one end connected to the panels, and weights connected to the other ends of said cables.

4. An automatic barricade for highway bridges comprising housings mounted beneath the floor of the bridge adjacent the ends of said bridge, said bridge floor having transversely extending slots therein communicating with the housings, channel guides depending from the bridge floor in the housings, panels slidable vertically in said guides and operable in the slots, said panels having openings therein, spring projected bolts slidably mounted on the housings and engageable in the openings for releasably securing the panels in lowered position, a cable connecting the bolts, said cable extending beneath the floor for engagement and actuation by said floor should it fall thereby retracting the bolts for releasing the panels, weights operatively connected to the panels for raising said panels to operative position, and gravity actuated dogs pivotally mounted in the housings and engageable beneath the panels for positively securing said panels in raised position.
